Marion Darrow

UNITED STATES PATENT OFFICE

LEO SCHAEFER, OF NEW YORK, N. Y.

FRAME WALLET

Application filed June 24, 1929. Serial No. 373,136.

This invention relates to improvements in wallets and pocketbooks, and it is the principal object of my invention to provide a wallet allowing a convenient opening for the deposition therein of bills etc., and which in its folded condition effectively prevents the purloining of money.

Another object of my invention is the provision of a wallet allowing a folding of the same into a comparatively small compass.

A further object of my invention is the provision of a wallet equipped with an inner partition for keeping bills assorted therein according to their denominations.

15 A still further object of my invention is the provision of a wallet or pocketbook allowing a folding of its longitudinal members along a median line and equipped with frames on the upper parts thereof hinged together, and provided on the hinge pintle with a spring having its ends straightened and bearing against the inner members of the frames for allowing the wallet to spring open upon the release of its locking catch 25 while a lower fold limits the width to which the wallet may be opened and prevents the loss of its contents.

It is also one of the objects of my invention to provide a wallet provided with a plurality 30 of card pockets and adapted to be folded along transverse creases into a small compass.

These and other objects of my invention will become more fully known as the description 35 thereof proceeds, and will then be specifically defined in the appended claims.

In the accompanying drawing, forming a material part of this disclosure:

Fig. 1 is a front elevation of a wallet or 40 pocketbook constructed according to my invention, closed.

Fig. 2 is a similar view of the wallet, open.

Fig. 3 shows the wallet, folded.

Fig. 4 is a sectional view, taken along line 45 4—4 of Fig. 2.

Fig. 5 is a perspective fragmentary view of the wallet, partly closed.

As illustrated, the wallet 10 of any suitable material, consists chiefly of two elongated 50 main parts or walls 11 and 12 adapted to

be folded upon one another along a median longitudinal crease 13 and to be folded in this position along transverse creases 14, 15 so as to form three parts 16, 17 and 18.

The upper part 18 has the edges of both 55 of its longitudinal parts 11 and 12 encased in frames 19 and 20 respectively hingedly connected, as at 21.

About the pintle of the upper hinge part a spring 22 is wound, the end 23 of which is 60 somewhat extended and bears against the inner member of frame 19, while the lower end of spring 22 is also extended and straightened to press or bear against the inner member of frame 20 as at 24.

65 Within the wallet, particularly the middle part 17 thereof, a partition wall 25 is provided for the separation of money notes of low and high denominations or of old and new notes, or the like.

70 The lower ends of elongated parts 11 and 12 are connected by a fold 26 to limit the width to which the wallet may be opened and to prevent bills and other contents to be unintentionally dropped from the wallet.

75 The outer face of the wallet has formed therewith pockets 27 and 28 respectively on parts 17 and 16 for the reception of cards, or the like.

80 A lock for locking frame parts 20 and 19 together when the wallet is folded comprises a handle or push button 29 made integral with a depending elastic member 30 secured at its lower end in frame 20, while the opposite end of the handle is shaped into a hook 31 adapted to engage an opening 32 in frame 19.

85 The operation of my device will be entirely clear from the above description and from the drawing, and it will be evident that after the bills etc., have been laid between walls 11 and 12 separating the bills of large denomination from those of small denomination by partition 25 the wallet is folded along its median line 13 and hook 31 is engaged in opening 32, the wallet will be closed and the lower flap 26 will effectively prevent the contents from falling out of the wallet.

90 An inwardly directed pressure on lip 29 will unlock the wallet and the ends 23, 24, 100

of spring 22 will facilitate the opening and spreading apart of parts 11 and 12, so as to give ready access to the interior of the wallet.

5 Cards etc., may be entered in pocket 27 and 28, and the wallet may then be folded along the creases 14 and 15 into its compact form illustrated in Figure 3.

10 It will be clear that upon folding frames 19 and 20 upon one another the snaplock will automatically close by a pressure exerted on frames 19, 20. The frame 19 may be made in form of a window for displaying photographs etc.

15 It will be understood that the above description and the drawing should be considered illustrative of my invention only, and that I may make changes therein within the scope of the appended claims without deviation from my invention.

20 Having thus described my invention what I claim as new and desire to secure by Letters Patent is:

25 1. A folding wallet composed of two elongated members adapted to be folded upon one another along their median line, transverse creases forming three endwise folding members and allowing a folding of the wallet into a small compass, frame members for the upper pair of said members, a locking means, 90 hinges connecting said pair of members, a means combined with said hinges for throwing the elongated members into unfolding position, a means for preventing loss and for 95 limiting the unfolding action of said elongated members, and a plurality of pockets on one of said members.

40 2. In a folding wallet of the class described, a pair of frame members hinged together at their inner meeting edges and adapted to receive and hold the material of the wallet, one having an opening, a lock on one of said frame members to engage the opening in said other frame member, a spring 45 wound about the hinge pintle, and having its ends straightened to press against the inner bars of said frame members to allow a ready and snappy unfolding of the wallet upon the release of said lock, and a fold at one end of 50 the wallet to limit its unfolding action.

55 3. A folding wallet comprising two elongated members adapted to be folded upon one another along their median line, transverse creases for allowing an endwise folding of the wallet in its longitudinally folded condition, frame members for one pair of said longitudinal members at one end thereof, locking means for said frame members, a partition within said wallet for separating bills 60 of high and low denominations, a fold at the end of the wallet opposite to said frame members, a hinge for said frame members, and means combined with said hinge to allow the wallet to spring open upon the release of said locking means, a frame for the reception of 65

photos and a plurality of pockets on one of said elongated members.

In witness whereof I have signed my name to this specification.

LEO SCHAEFER.
